UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY

JIG FOR LAST-DRILLING MACHINES

Application filed June 16, 1926. Serial No. 116,351.

This invention relates to machines for making holes in lasts and is illustrated as embodied in a machine of the type set forth in United States Letters Patent No. 1,624,916, granted April 19, 1927, on my application.

Machines of the type referred to are designed to bore holes through the rear ends of lasts from the heel seat faces of the lasts to the tops of the cones of the lasts to adapt each last to receive a screw fastener which is passed through the last and through the heel seat of a shoe on the last into a wood heel on the shoe as a temporary means for securing together the heel, the shoe and the last in accordance with the method disclosed in co-pending application, Serial No. 367,173, filed April 29, 1924, Patent No. 1,615,258 dated Jan. 25, 1922, in the name of Maurice V. Bresnahan. For this purpose such a machine comprises a drill and last holding means, the latter including a member arranged to engage a previously formed hole in the central portion of the heel plate of the last and another member arranged to enter the usual spindle or thimble hole of the last to co-operate with the first-mentioned member to position the heel end of the last transversely with respect to the axis of the drill. Provision is also made in such a machine for tilting a last longitudinally to predetermine the angle of the hole longitudinally of the last to insure that the drill will not encounter any obstruction such, for example, as a rivet or other fitting in its passage through the last and to permit variation in the angle of the hole, if desired, in accordance with the style or shape of a particular type of heel so that the screw fastener may be driven into the heel at the angle best adapted to facilitate secure attachment of the heel. While machines so organized have operated accurately and otherwise satisfactorily it has been found that sometimes the holes in the heel plates have not been uniformly located transversely of the heel seat surfaces of the lasts and that, similarly, variations in the positions of the thimble holes transversely of the lasts have been encountered.

In view of these conditions one object of the present invention is to provide an im-

proved machine of the general type above referred to which will be so organized as to insure that the holes made in the lasts will terminate at points accurately located in predetermined relation transversely of the lasts, in the top and heel seat faces of the lasts, while at the same time providing for any desired longitudinal tilting adjustment of the lasts in such a manner as not to interfere with the desired accurate location of the holes transversely of the last.

To the accomplishment of this object, one feature of the present invention consists in the provision of an improved machine comprising a drill, and a jig for holding a last and predetermining in definite transverse relation to the last the locations in the top and bottom faces of the last of the opposite ends of the hole to be bored by the drill, the drill and the last holding part of the jig being relatively movable to permit longitudinal tilting adjustment of the last to vary the angle of the hole longitudinally of the last without changing the locations of the ends of the hole transversely of the last.

In the illustrative embodiment of the invention herein shown, the means for predetermining the transverse locations of the opposite ends of the hole in the last comprise a device arranged to engage the last (or the outside of a shoe on the last) at spaced points around the top portion of the last or the shoe and other members arranged similarly to engage the outside of the shoe at spaced points around its counter portion near the bottom thereof, said device functioning independently of said members to position the top of the last in a predetermined transverse relation to the axis of the drill and said members operating independently of said device to center the bottom of the last transversely relatively to the drill. The device for engaging and centering the top portion of the last is adjustable so that it may be set to position the top of the last in a transverse central relation to the drill axis or to position the top of the last eccentrically with respect to the axis of the drill sufficiently to compensate for the thrust of the drill so that after the hole has been bored it will be accurately cen-

tered in respect to the top as well as with respect to the bottom of the last. The illustrated construction by means of which the above described transverse positioning of the last is effected is further such as to permit longitudinal tilting adjustment of the last to vary the angle of the hole lengthwise of the last without disengaging the last from either the last top or bottom positioning means as well as without affecting or disturbing the location of either end of the hole transversely of the last. To accomplish the above results provision is made, as shown, for tipping the last longitudinally about an axis which is perpendicular to the axis of the drill and which is arranged to intersect the drill axis at the center of the seat surface of the last.

Another object of the invention is to provide an improved machine of the type referred to in which the last supporting and positioning means may be adjusted to enable them to receive lasts presented thereto at any angle which may be found most convenient for an operator.

With this object in view, another feature of the invention consists in the provision of a last holding and positioning jig or fixture which is provided with novel means for predetermineding the angular relation of a last to a drill and which is adapted to be tiltably adjusted bodily about an axis coincident with the axis of the drill to facilitate the presentation of lasts to the device at different angles.

Further objects and features of the invention will be explained in the following description, reference being had to the accompanying drawings, in which

Fig. 1 is a view in front elevation of a portion of a machine embodying the features of the invention;

Fig. 2 is a view, partially in elevation and partially in section, of a portion of the machine showing particularly the work positioning devices and their relation to the drill, the work positioning devices being shown as they would appear to an observer looking in the direction of the arrow X in Fig. 4;

Fig. 3 is an elevational view, as seen from the left-hand end of the machine, of the device for locating the lower portion of the heel end of a last relatively to the drill;

Fig. 4 is an elevational view of the right-hand end of the machine; and

Fig. 5 is a plan view of the portion of the machine shown in Fig. 1, the work locating and holding devices being shown as they appear when viewed in the direction of the arrow Y in Fig. 4.

Referring to the drawings, the machine therein shown consists of a drill 8 and a jig or fixture 10. The drill 8 is rigidly secured to one end of the armature shaft of an electric motor (not shown). The jig 10, comprising last positioning and holding devices, is supported upon a carriage 20 slidably

mounted upon a horizontal guide rod 12, the ends of which are secured in lugs (such as the lug 14 shown in Fig. 1) formed upon a base 16 upon which the motor may be mounted. The guide rod 12 is parallel to the axis of the drill and in order that a last held by the jig 10 may be moved toward the drill to cause the drill to bore through the last, the carriage 20 is arranged to be moved toward and from the drill on the guide rod 12 between suitably positioned stops by means of a hand lever not herein shown but which may be connected with the carriage by means of a link 22 (Fig. 1) in a manner similar to that described in my Letters Patent above referred to. The drill 8 extends through a bearing sleeve 18 which is supported in a portion of the jig 10. The above described mounting and arrangement of the drill and the motor as illustrated is substantially the same as that disclosed in said Letters Patent, although in the present machine the bearing sleeve through which the drill extends is differently constructed and mounted since it now constitutes no part of the work holding or positioning means. The illustrated last positioning and holding devices are carried by two frames 26 and 28, the frame 26 being made in the form of a closed yoke and being mounted for tilting adjustment about a horizontal axis coincident with the axis of the drill, while the frame 28 is mounted within the yoke-shaped frame 26 and is pivoted to the sides of the yoke for angular or tilting adjustment about an axis which is perpendicular to the drill axis and which is further so disposed with respect to the last holding and positioning devices as to intersect the drill axis at the center of the heel seat surface of a last, such as the last L, supported by the holding device.

The outer or yoke-shaped frame 26 is provided at one end with a hollow hub 32 which is received within a split bearing sleeve 30 formed on the carriage 20 in axial alinement with the drill guiding sleeve 18. The hub 32 is adapted to be rotatably adjusted in the sleeve 30 for the purpose of tilting the frame 26 about the axis of the drill and a clamping bolt 34 extends through the split portion of the bearing sleeve 30 for the purpose of tightening the sleeve upon the hub 32 to secure the frame 26 in adjusted position. This construction enables the last holding and positioning devices to be tilted so that a last may be presented thereto in an inclined position which may be found most convenient for the operator, it being pointed out that when a last is held by grasping its forepart with one hand it is more natural to present it to the holding devices in an inclined than in a substantially horizontal or in a substantially vertical position.

At the end of the outer frame 26 opposite the hub 32 an aperture is formed to receive a bushing 36 within which the sleeve 18 is

adapted to turn freely. The sleeve 18 is held against axial displacement within the bushing 36 by means of an annular shoulder 38 at one end of the sleeve and a collar 40 which is secured to the opposite end of the sleeve, said collar and shoulder engaging opposite ends of the bushing 36. As shown, a lug 42 (Fig. 2) formed upon the interior of the bearing sleeve 18 projects into the flute of the 10 drill, thus connecting the sleeve to the drill so that while the sleeve and the drill will turn in unison within the bushing 36 when the drill is not operating upon the work the sleeve 18 is capable of sliding longitudinally 15 relatively to the drill. Thus, when the carriage 20 with the jig 10 is advanced to present at last to the drill the sleeve 18 is caused to slide longitudinally of the drill, the lug 42 riding along the flute of the drill in a direction 20 away from the point or free end of the drill. Upon the return movement of the carriage 20 the lug 42 travels in the opposite direction, that is, toward the point of the drill at which time it functions to clear the 25 flute of the drill of any chips which may have accumulated therein as a result of the preceding boring operation.

The inner frame 28, as shown in Figs. 1 and 2, consists of a substantially L-shaped member having a portion 29, constituting the shorter leg of the L, which is apertured at 31 to permit the passage of the drill therethrough. The portion 29 of the frame 28 is provided with alined trunnions 44 which are 35 received in bearings in the opposite sides of the outer frame 26, this arrangement enabling the inner frame 28 to be tilted about an axis at right angles to the axis of the drill, thus providing for variation in the longitudinal angular relation of the last with respect to the drill so that a hole may be bored at any desired angle longitudinally of a last without changing the location of the end of the hole in the last bottom. For securing 40 the inner frame 28 in different positions of tilting adjustment relatively to the outer frame and to the axis of the drill, a binding screw 46, having threaded engagement with the inner frame 28, extends through an arcuate slot 48 in the outer frame 26, the arcuate slot being curved about a center within the common axis of the trunnions 44. Upon loosening the binding screw 46, tilting adjustment of the inner frame 28 may be 45 effected manually merely by grasping a convenient portion of the inner frame and tilting it as may be required.

For the purpose of supporting a last while it is being operated upon by the drill, the 50 portion 29 of the frame 28 is provided with two raised bearing surfaces 50 and 52 (Fig. 1) constituting a two-point bearing for the last bottom, and the opposite end portion of the frame 28 carries a clamp member 54 for 55 engaging the top face of the cone of the last

to co-operate with the bearing surfaces 50 and 52 securely to hold the last in place in the jig 10. The bearing surface 50 is arranged to engage the heel seat portion of the last at a point forward of the center of the heel seat, while the bearing surface 52 consists of the inclined face of a cam or wedge block 56 which is adjustably mounted upon the portion 29 of the frame 28 and which is arranged to engage the rear edge portion of the last bottom. The clamp member 54 is carried at the inner end of a rod 58 which is screw-threaded through the outer end portion of the longer arm of the frame 28 and is provided at its outer end with a knurled head 60 by means of which it may be turned to move the clamp member 54 into and out of holding engagement with the last. As shown, the clamp member 54 has a ball and socket joint connection with its supporting rod 58 which enables it readily to adjust itself to the plane of the top surface of the cone of the last which it engages.

Before the clamp member 54 is manipulated, however, to clamp the last in position to be drilled, the last is positioned both longitudinally and transversely with respect to the drill so that the latter will enter the last at the center of the heel seat surface of the last bottom and will make a hole extending 90 through the last and terminating at a predetermined location transversely of the top surface of the cone portion of the last. For the purpose of locating the last longitudinally for the drilling operation, the inclined 95 surface 52 of the cam or wedge block 56 is interrupted by means of a notch which extends transversely across said face and provides a shoulder 62 which serves as an abutment to limit the rearward movement of the 100 last and positively to locate the last longitudinally with the center of its heel seat surface in line with the drill. As the last is being pushed rearwardly over the inclined 105 face of the wedge block 56 said face functions to impart a slight longitudinal tilting movement to the last for a purpose hereinafter to be described.

To adapt the positioning shoulder 62 for use with lasts of different sizes the wedge 115 block 56 is made adjustable toward and from the axis of the drill. To this end, the wedge block is provided with a rearwardly extending shank portion 64, as shown in Fig. 5, which is slidably mounted in a guideway in 120 a lug 66 formed on the portion 29 of the frame 28 and is provided with a series of notches 68 adapted to be selectively engaged by the periphery of a locking disk 70. The locking disk 70 is mounted to turn upon a rod 72 125 which is parallel to the shank 64 and is splined in the lug 66. Normally, the locking disk 70 is held in a rearward position against a head 74 on the rod 72 by means of a spring 76 which is coiled around the rod 130

72 between the locking disk and the lug 66. To enable the locking disk to be disengaged from one of the notches 68 in the shank which carries the wedge block a portion of the periphery of the disk is cut away to form a flat 5 surface 78 (Figs. 1 and 5). By turning the locking disk until the flat face 78 is opposite the shank 64 the disk will be disengaged from the shank and the shank and the disk 10 may be relatively shifted to bring another one of the notches 68 into engagement with the disk, thus shifting the location of the wedge block and the locating shoulder 62 relatively to the drill. When the rearmost notch 68 is 15 engaged by the locking disk 70 the locating shoulder 62 is located to position the smallest size last properly in a lengthwise direction with respect to the drill. This setting of the locating shoulder and wedge block is adapted for use with several of the smaller sizes of lasts. For several of the next larger sizes the locking disk 70 should be engaged with the second notch 68 while the remaining notches 68 may be engaged by the locking disk for 20 the purpose of positioning the locating shoulder 62 for use in connection with lasts of still larger sizes.

In addition to being located longitudinally, as just described, the last is also located transversely with respect to the drill in a manner to insure the greatest accuracy in determining the locations of the opposite ends of the fastener-receiving hole in the top and bottom faces, respectively, of the last. To this end 30 separate devices are provided for independently locating the bottom and top portions of the heel end of the last transversely relatively to the drill.

The means for transversely locating the 40 bottom portion of the heel end of the last comprises a last centering device which is shown in detail in Fig. 3. This last centering device comprises a pair of centering fingers 80 which are pivotally mounted upon 45 the portion 29 of the frame 28 at points equally spaced at opposite sides of the drill. To enable them to perform their last centering function these fingers 80 are arranged to engage opposite sides of the last at points 50 near the last bottom and they are spring pressed inwardly and are connected together for movement both inwardly and outwardly in unison. The inner end of each centering finger 80 is made in the form of a yoke, as 55 shown at 81, to straddle the portion 29 of the frame 28, and the ends of the yoke portions 81 are mounted upon pivot studs 82 carried by the frame 28.

To insure that the centering fingers 80 60 shall move in unison toward and from each other the yoked portions of the fingers are provided with extensions 84 which approach each other and are operatively connected with a head 86 on a slide rod 88 which is mounted 65 in a bearing lug 90 formed on the frame 28.

The connections between the extensions 84 of the centering fingers 80 and the head 86 comprise pins or studs 92 which are carried by the extensions 84 and are received in notches 94 in the head 86. To hold the centering fingers normally in positions to be engaged and spread apart by a last the slide rod 88 is 70 acted upon by a spring 96 which is coiled about the rear end of the rod 88, one end of the spring engaging the lug 90 while the opposite end of the spring engages the innermost of two nuts 98 on the rod 88. The limit of approach of the centering fingers 80 is determined by means of an adjustable abutment 75 in the form of a screw 100 which extends through the lug 90 and is adapted to be held in adjusted position by a set screw 102. The nuts 98 may be turned to vary the tension of the spring 96 so as to regulate the pressure exerted by the centering fingers upon the last 80 and a handle 104 is connected with one of the centering fingers by means of which the force tending to move these fingers inwardly 85 may be relieved if desirable to facilitate the introduction of the last between them.

The means for locating the upper portion of the rear end of the last transversely with respect to the drill comprises a locating device indicated at 108. This device 108 is provided with a pair of oppositely inclined locating faces 110 arranged to engage the opposite lateral edges of the top face at the heel end of the last. The locating faces 110 are carried by a head 112 which is rigidly secured to the inner end of a hollow shaft 114 that is splined within the hollow hub 32 of the outer frame 26. For the purpose of causing the locating device 108 to engage a last 90 yieldingly, the head 112 is acted upon by a coiled spring 116 which is arranged within the hollow shaft 114, the spring acting at one end against a shoulder formed at the inner extremity of the recess in the shaft 114 and at the other end against the base of a thimble 118 which is secured by means of screws 120 to the outer end of the hub 32, the interior 100 of the thimble 118 being alined with the shaft 114 and adapted to receive the latter as the locating device 108 is displaced by engagement of a last therewith or as the said device 110 is adjusted for use in connection with the larger sizes of lasts. The inward movement of the locating device 108 under the influence of the spring 116 is limited by the engagement 115 with the end of the thimble 118 of a knurled nut 122 on a rod 124 which extends through the thimble and the hollow shaft 114 within the coils of the spring 116 and is secured at its inner end to the head 112. By 120 turning the nut 122 the locating device 108 may be located relatively to the last supporting surfaces 50 and 52 as best adapted for the height of the last to be operated upon. On account of the length of the spring 116 such 125 adjustment of the locating device 108 will 130

not materially affect the tension of the spring 116. To insure that the locating device 108 may be firmly secured in adjusted position heightwise of the last a spring finger 126 secured to the thimble 118 is arranged to interengage with the serrations on the periphery of the knurled adjusting nut 122.

The action of the drill on the last may have some tendency to displace the last slightly from its transversely located position. To offset any such tendency of the drill it may be desirable to locate the inclined faces 110 of the positioning device 108 so that the upper portion of the last will be slightly offset laterally from a true central position with respect to the axis of the drill. To enable such an adjustment to be effected, the inclined faces 110, as shown, are formed upon plates 128 which are secured to the head 112 by means of screws 130 which extend through longitudinal slots 132 in said plates and are threaded into the head 112. This arrangement enables the plates 128 to be adjusted in either direction transversely of a last engaged thereby to compensate for the lateral thrust of the drill, or to insure that the upper portion of the last is located centrally with respect to the drill axis, as may be desired. If found to be unnecessary to compensate for the thrust of the drill the plates 128 will be adjusted so as accurately to centralize the top portion of the cone of the last transversely relatively to the drill.

When a last is to be drilled by means of the illustrated machine the forepart of the last is grasped by the operator and the heel end of the last is presented to the work positioning devise of the machine. As hereinbefore mentioned a last, when grasped by the forepart, is most naturally held in a position inclined more or less sharply to the horizontal and with the heel end of the last uppermost. In order to receive a last presented thereto in such an inclined position the outer frame 26 of the machine may be adjusted into some such angular position as that indicated in Figs. 1 and 4, and rigidly secured in this position by means of the binding screw 34. The inner frame 28 will be manually adjusted 50 (angularly about its trunnions 44) so that when a last has been clamped in place it will be so positioned relatively to the drill that the hole bored by the latter will extend through the last at approximately the desired angle longitudinally of the last. If it should be found that the drill in passing through the last would encounter a metallic fitting, such as a rivet, or any other obstruction, the path 55 of the drill through the last may be changed by tilting the frame 28 about its trunnions 44 to change the longitudinal angular relation of the last to the drill. The frame 28 may be adjusted in a similar manner for the purpose of adapting the angle of the hole in the

last to the shape or style of a particular type of heel which is to be used.

As the heel end of the last is presented to the locating devices, the heel seat surface of the last engages first the raised bearing face 50 and thereafter engages and slides over the inclined face of the cam block 56 until the rear edge of the heel plate or rear end portion of the last bottom engages the shoulder or abutment 62 on the cam block. The shoulder 62 arrests the rearward movement of the last and locates the last with the longitudinal center of its heel seat portion intersecting the axis of the drill. As the last is pushed rearwardly into the machine the lower portion of its heel end enters between the centering fingers 80 which yield outwardly in unison and in equal amounts, thus serving to center the lower portion of the heel end of the last transversely with respect to the drill. The upper portion at the heel end of the last is centered or located transversely with respect to the drill independently of the lower portion of the heel end, this being desirable on account of the fact that the upper portion of the last is usually not in alinement with the transverse center of the bottom portion of the last, but is offset more or less to one side or the other according to whether the last is for a right or a left shoe. To insure that the inclined face 110 of the locating device for the upper portion at the heel end of the last shall function properly said device is mounted so as to yield somewhat heightwise of the last as the last is being moved into engagement therewith. In order that the device 108 shall be so positioned as not to interfere with the convenient introduction of the last into the machine the device is preferably adjusted by manipulation of the nut 122 in such spaced relation to the bearing surface which engages the last bottom that as the last is being pushed rearwardly across the bearing face 50 the cone of the last will slide between the faces 110 without effecting any substantial outward displacement of the head 112. However, as the rear end portion of the last bottom engages and rides upwardly over the inclined surface of the wedge block 56 the last is tilted bodily in such a manner as to move the cone portion of the last outwardly in the direction of the axis of the shaft 114 which carries the head 112, thus causing the head 112 to yield outwardly against the action of the spring 116 and insuring that both inclined faces 110 function properly to position the top of the last transversely with respect to the drill. As hereinbefore pointed out the adjustment of the plates 128 which is permitted by the screw and slot connections 130, 132 between the plates and the head 112 enables the top portion of the last to be located transversely in such a position that the center of the top face will be somewhat offset from the path 130

of the drill to compensate for such slight transverse bodily displacement of the last as may result from the sidewise thrust of the drill as it is passed through the last.

Having described my invention, what I claim as new and desire to secure by Letters Patent of the United States is:

1. In a drilling machine for lasts, a last holding and positioning device having means constructed and arranged to predetermine the transverse relation relatively to the drill of the bottom of the last and means to locate the top of the last in predetermined eccentric relation transversely with respect to the axis of the drill to compensate for the thrust of the drill.

2. In a drilling machine for lasts, a last holding and positioning device comprising a frame tilttable about an axis transverse to the axis of the drill to vary the angle lengthwise of the last of the hole to be made by the drill, means on said frame for locating the bottom of the last transversely with respect to the drill, a second frame carrying the first frame and having a device yieldably mounted thereon for positioning the top of the last transversely with respect to the drill, and a cam member on the first frame for tilting the last longitudinally as it is moved into engagement with said member to insure yielding engagement of the last with said yieldingly mounted member.

3. In a drilling machine for lasts, a carriage slideable axially of the drill, a last holding device pivotally mounted on the carriage for tilting adjustment about an axis intersecting the axis of the drill, means on the carriage for centering the bottom of the last transversely relatively to the drill, a yieldingly mounted device for determining the transverse position of the top of the last relatively to the drill, a spring arranged to press said device toward said centering means, a cam member on the last holding device for forcing the last into yielding engagement with said yielding device, and means for limiting the movement of said device under the action of the spring.

4. In a drilling machine for lasts, a carriage slideable axially of the drill, a last holding device pivotally mounted on the carriage for tilting adjustment about an axis intersecting the axis of the drill, means on the carriage for centering the bottom of the last transversely relatively to the drill, a yieldingly mounted device for determining the transverse position of the top of the last relatively to the drill, a spring arranged to press said device toward said centering means, a cam member on the last holding device for forcing the last into yielding engagement with said yielding device, and means for varying the extent of compression of the spring.

5. In a drilling machine for lasts, a carriage slideable axially of the drill, a frame pivotally mounted on the carriage for tilting adjust-

ment about an axis coincident with the axis of the drill and having means for positioning the top of a last relatively to the drill, a second frame pivotally mounted on the first frame for angular adjustment about an axis perpendicular to the drill axis, and means on the second frame for positioning the bottom of a last transversely relatively to the drill and for rigidly supporting the last in transversely adjusted position, the axis of tilting adjustment of the second frame being arranged to intersect the drill axis at the center of the heel seat surface of the last.

6. In a drilling machine for lasts, a carriage slideable axially of the drill, a frame pivotally mounted on the carriage for tilting adjustment about an axis coincident with the axis of the drill and having means for positioning the top of a last relatively to the drill, means for rigidly securing said frame in adjusted position relatively to the carriage, a second frame pivotally mounted on the first frame for angular adjustment about an axis perpendicular to the axis of the drill, means on the first frame for securing the second frame in angularly adjusted position, and means on the second frame for positioning the bottom of the last transversely relatively to the drill and for rigidly supporting the last.

7. In a drilling machine for lasts, a carriage slideable axially of the drill, a frame pivotally mounted on the carriage for tilting adjustment about an axis coincident with the axis of the drill and having means for positioning the top of a last relatively to the drill, means for rigidly securing said frame in adjusted position relatively to the carriage, a second frame pivotally mounted on the first frame for angular adjustment about an axis perpendicular to the axis of the drill, means on the first frame for securing the second frame in angularly adjusted position, means on the second frame for positioning the bottom of the last transversely relatively to the drill, a two point bearing on the second frame for engaging the heel seat surface of the last, and adjustable means for engaging the top of the cone of the last and co-operating with said two point bearing for holding the last in place.

8. In a drilling machine for lasts, a carriage slideable axially of the drill, a frame pivotally mounted on the carriage for tilting adjustment about an axis coincident with the axis of the drill and having means for positioning the top of a last relatively to the drill, means for rigidly securing said frame in adjusted position relatively to the carriage, a second frame pivotally mounted on the first frame for angular adjustment about an axis perpendicular to the axis of the drill, means on the first frame for securing the second frame in angularly adjusted position, and means on the second frame for

centering transversely and longitudinally the bottom of the last relatively to the drill.

9. In a drilling machine for lasts, a carriage slidable axially of the drill, a frame pivotally mounted on the carriage for tilting adjustment about an axis coincident with the axis of the drill and having means for positioning the top of a last relatively to the drill, means for rigidly securing said frame in adjusted position relatively to the carriage, a second frame pivotally mounted on the first frame for angular adjustment about an axis perpendicular to the axis of the drill, means on the first frame for securing the second frame in angularly adjusted position, means on the second frame for transversely centering the last with respect to the drill, and adjustable means on the second frame for determining the position of the last longitudinally with respect to the drill.

10. In a drilling machine for lasts, a carriage slidable axially of the drill, a frame pivotally mounted on the carriage, centering fingers mounted on said frame and connected for engaging opposite sides of the lower portion at the heel end of a last and connected to move uniformly when separated by the introduction of a last between them, means for adjusting the limits of approach and separation of said fingers, means for engaging the heel seat surface of the last including a cam member for tilting the rear end of the last, yielding means for co-operating with said cam member to center the upper portion at the rear end of the last transversely with respect to the drill, and means co-operating with the heel seat surface engaging means for rigidly supporting the last while it is being drilled.

In testimony whereof I have signed my name to this specification.

FREDERIC E. BERTRAND.
